UNITED STATES PATENT OFFICE.

FRANK C. WATKINS, OF PHILADELPHIA, PENNSYLVANIA, ASSIGNOR, BY MESNE ASSIGNMENTS, TO THE UNITED STATES KROTOPHONE COMPANY, OF NEW YORK, N. Y.

CENTRAL-OFFICE TELEPHONE SWITCH-BOARD.

SPECIFICATION forming part of Letters Patent No. 355,425, dated January 4, 1887.

Application filed April 21, 1886. Serial No. 199,718. (No model.)

To all whom it may concern:

Be it known that I, FRANK C. WATKINS, a citizen of the United States, residing at Philadelphia, in the county of Philadelphia and State of Pennsylvania, have invented certain new and useful Improvements in Central-Office Telephone Switch-Boards; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to telephonic central-office switch-boards, and the object of the invention is to provide a simple and reliable switch for connecting one line with another; and the novelty consists in the combination, construction, and arrangement of the parts of the same, as will be hereinafter more fully described, and particularly pointed out in the claim.

In the accompanying drawings, similar letters of reference indicate like parts of the invention.

Figure 1 is a front elevation of my improved switch-board, and Fig. 2 is a transverse vertical section through one of the vertical line-strips.

A is the frame, and the face of it is provided with a series of metallic strips, B, and above each strip is an annunciator, C, the subscriber's line D running through the annunciator 35 C to the binding-post, connected to the strip B.

F F is a series of hooked levers fulcrumed in the strip B, their hooked ends having a detachable weight, G, hung thereto, while the rear end of each lever extends through the 40 frame A, and each one is provided with a contact-spring, H, which forms a connection with one of a series of longitudinal metallic strips, I, extending across the back of the frame, and when a weight is hung on the hooked end of 45 the lever the contact-spring on that lever is connected to the metallic strip behind it.

The normal condition of the board is as follows: The top longitudinal strip, I', is connected with the ground, and each line comes 50 in through its annunciator and through the

top hooked lever to the ground. A row of weights being hung on the row of top levers, when a subscriber calls his annunciator drops, which notifies the attendant, and he removes the weight from the top lever and places it on any one of the levers not in use on the same vertical strip. This connects that strip with the corresponding longitudinal strip on the back, and by removing the weight from the called subscriber's vertical strip and placing it on the lever corresponding to the longitudinal strip on which the calling subscriber's line is switched the two are ready for communication, and when through the weights on both strips are replaced on the top levers, as above described. For example, suppose the fourth subscriber from the left wishes to communicate with the seventh. When the fourth calls "central office" his annunciator drops and he notifies the operator to connect him with number seven. The operator then removes the weight from its place on the top lever, which takes it off the ground, and places the weight on any one of the lower hooks on the same vertical strip, and at the same time removes number seven's weight from the top lever and places it on the lever corresponding to the longitudinal strip on the back, on which the calling subscriber's weight was placed, and the two subscribers are in communication.

Having thus described my invention, what I claim as new and useful, and desire to secure by Letters Patent of the United States, is—

A switch-board provided with a series of vertical metallic strips, each one of which is 85 connected to an individual line through an annunciator, and having a series of weighted levers, in combination with a series of longitudinal metallic strips arranged across the back of the board, whereby a weight attached 90 to the hooked end of one of the levers will connect it with the corresponding strip on the back, substantially as shown and described.

In testimony whereof I affix my signature in presence of two witnesses.

FRANK C. WATKINS.
